TYPOGRAPHICAL COMPOSING MACHINE

William Ackerman, Towners, and George P. Kingsbury, Hollis, N. Y., assignors to Mergenthaler Linotype Company, a Corporation of New York

Application September 11, 1929
Serial No. 391,752

10 Claims. (Cl. 199—29)

This invention relates to typographical composing machines, such as linotype machines, wherein circulating matrices are released from a magazine in the order in which their characters are to appear in print and then composed in line in an assembling elevator, the composed line transferred to the face of a mold, the mold filled with molten metal to form a slug or linotype against the matrices which produce the type characters thereon, and the matrices thereafter returned to the magazine from which they started. The matrices most commonly employed in these machines are of the two-letter variety, that is to say, matrices bearing on their casting edges two superposed characters of the same body size but of different face (usually one roman and the other italic), and means are provided whereby the matrices passing to the line may be composed at two different levels in order to bring the upper or lower characters into casting position as desired. In the standard commercial machines, the assembling elevator is equipped with what is known as an auxiliary duplex rail which comprises a relatively fixed long section and movable short section, the latter being arranged at the receiving end of the elevator and adjustable into and out of the path of the incoming matrices so as to arrest them at the upper level or allow them to pass to the lower level, and the former serving to maintain the arrested matrices at the upper level as the composition of the line progresses. Lines made up wholly of roman or italic characters, or lines made up of both kinds of characters, may in this 35 way be composed by an adjustment of the short rail section prior to or during the composition of the line.

The present invention relates, more particularly, to automatic machines, such as those operated by a perforated tape or strip, and contemplates the operation of the short assembler rail section automatically by special symbols produced in the perforated tape, the idea being to adapt these automatic or tape-controlled machines to handle the regular two-letter matrices as well as single letter matrices. The exact manner in which this is accomplished will best be understood from the detailed description to follow.

In the accompanying drawings, the invention has been shown merely in preferred form and by way of example, but obviously many changes and variations may be made therein and in its mode of operation, which will still be comprised within its scope. It is, therefore, to be understood that the invention is not limited to any

specified form or embodiment except in so far as such limitations are specified in the claims.

Referring to the drawings:

Fig. 1 is a front view of an automatic or tape-controlled linotype machine equipped with the present improvements;

Fig. 2 is a horizontal section taken through the keyboard mechanism, showing in plan the assembling elevator and the electrical distributing device;

Fig. 3 is a vertical section taken through the keyboard mechanism, showing the lower end of a magazine and intermediate connections;

Fig. 4 is a side elevation of the electrical distributing device, showing in perspective the means for operating the assembler rail and, diagrammatically, the various electrical connections between the parts;

Fig. 5 is an enlarged front elevation, partly in section and broken away, of the tape feeding mechanism and the electrical distributing device;

Fig. 6 is a horizontal section taken on the line 6—6 of Fig. 5;

Fig. 7 is an enlarged fragmentary front elevation, showing the manner of assembling matrices at the upper level;

Fig. 8 is a view similar to Fig. 7, showing the manner of assembling matrices at the lower level;

Fig. 9 is a detail plan view of the receiving end of the improved assembling elevator;

Fig. 10 is an enlarged horizontal section, showing the duplex rail and parts associated therewith;

Fig. 11 is a vertical section taken on the line 11—11 of Fig. 10; and

Fig. 12 is a diagram, showing the electrical connections by which the tape controls the operation of both the matrix releasing mechanism and the adjustable short rail section.

The matrices X (see Fig. 3), of the regular "two-letter" variety, are stored in the inclined channelled magazine A and are released therefrom one at a time under the control of escapements A¹, the latter being actuated by a series of vertical reciprocating reeds A², through a corresponding series of pivoted levers A³, from a tape-controlled keyboard mechanism, later to be described.

The matrices, as released, are directed by the usual channel front plate B (Fig. 1) onto a constantly driven inclined belt B¹, which delivers them, one after another, in the order of their release to an assembling elevator or assembler

C, wherein they are composed in line under the influence of a star wheel D, against an upstanding finger E¹ of a spring controlled resistance slide E. After composition, the elevator C is raised to position the line between the depending fingers f of a transfer slide F, which thereupon forwards the line to the casting mechanism, all as is well understood in the art.

The elevator C is provided with a pair of horizontal matrix supporting rails C¹ upon which the matrices are assembled at the lower lever to locate the upper characters in casting position, and with a so-called duplex rail C² arranged above the front rail C¹ and upon which the matrices may be assembled at the upper level to bring their lower characters in casting position. The auxiliary rail C² consists of a relatively short section C³ arranged at the receiving end of the elevator and a longer section C⁴, which latter forms a continuation of the short section and serves to maintain the matrices at the upper level as they are pushed off the short section. The short rail section C³ is slidably mounted in the front wall of the elevator C and is adjustable back and forth into and out of the path of the descending matrices X, being adapted in its rear or active position to arrest the matrices at the upper level and in its forward or inactive position to allow sufficient space between the star wheel and the adjacent end of the long rail section C⁴ for the matrices to pass freely to the lower rails C¹.

As the assembling elevator is ordinarily constructed, in the composition of lines containing both roman and italic characters, one or more matrices remain upon the short rail section when it is desired to assemble the next succeeding matrices at the lower level, and it is common practice at such times to delay the adjustment of the short rail section to its inactive position until the said succeeding matrices, under the influence of the star wheel, have advanced those upon the short rail section off the same and onto the longer section of the duplex rail. In the present instance, however, and primarily for reasons later to appear, the adjustable rail section C³ (see Figs. 7 to 11 inclusive) is made substantially shorter than the standard rail section, and the star wheel is arranged to push the individual matrices off said rail section immediately they enter the elevator, so that this rail section will always be clear of matrices and may therefore be adjusted to its inactive position at any time without danger of dropping matrices to the lower rails C¹.

The star wheel D, as will be noted (Figs. 7 and 8), is substantially elliptical in form, presenting only two points instead of the usual four, and is adapted at each half rotation to present a reduced face portion to the descending matrices so as to afford ample space for the latter to clear the exposed end of the long section C⁴ of the duplex rail when the short section C³ is out of action. While the room thus provided is somewhat less than that ordinarily allowed, suitable compensation for the difference is made by a guard or deflector C⁵, which is intended, in the inactive position of the short rail section C³, to guide the matrices past the rail section C⁴ and thus insure their delivery to the lower rails C¹.

The short section C³ of the duplex rail C² (as best shown in Fig. 10) is carried by one arm of a horizontal U-shaped slide plate C⁶, which is apertured at c to receive the upper end of a

vertically disposed operating lever C⁷ and is also formed with a stop shoulder c¹ adapted by its engagement with the front face of the elevator to limit the inward movement of the plate C⁶ and locate the rail section C³ in its active position. The movement of the plate C⁶ in the opposite direction is limited by the engagement of the offset end portion of the short rail C³, with the rear wall of a recess c² formed in an upright side member of the elevator (see Fig. 3). The deflector C⁵ rises from one end of a horizontal lever C⁸, pivotally mounted on the body portion of the long rail section C⁴ (the latter being fixed and connected at its opposite end to the other arm of the U-shaped plate C⁶).

The foregoing arrangement is such that when the plate C⁶ is pushed rearwardly to locate the short rail section in its active position, the deflector C⁵, through the lever C⁸, will be moved forwardly out of the path of the descending matrices (see the full line showing in Figs. 10 and 11), and when the plate C⁶ is pulled forwardly to draw the rail section C³ out of action, the deflector will be moved rearwardly and its guiding edge located directly above the contiguous end of the fixed rail section C⁴, (see the dotted line showing in said figures). In order that the deflector C⁵ under the latter adjustment may clear the lower projecting ears of matrices supported by the long rail section C⁴, it is formed in its rear face with a recess c³ (see Fig. 8). Hence, it will be seen that the level at which the matrices are composed may be properly controlled by a single adjustment of the plate C⁶ and this without regard to the matrices already assembled.

The above described improvements in the assembling elevator in themselves are the invention of another but their use in connection with the automatic or tape-controlled mechanism about to be described constitutes a part of the present invention. In this connection, however, it may be stated that the present invention contemplates any other form or arrangement of the parts which will allow the matrices to be assembled at different levels during the composition of a line, whether the number of matrices assembled at the upper level at any place or places in the line be one only or a larger number.

The keyboard mechanism provided for effecting the release of the individual matrices from the magazine A, like that employed in the well-known teletypesetter, is controlled automatically through suitable electrical devices (presently to be described) from a perforated tape T, the symbols of which are produced therein according to a definite code or system to represent the matrices and spacers to be released in composing the lines. This mechanism (see Figs. 1, 2 and 3) is carried in a frame G arranged at the rear of the keyboard H and fastened to upright side posts G¹, G² rising from fixed bracket members H¹ of the keyboard base frame H². The operative elements thereof consist of a series of vertical slides G³ mounted and guided in the frame G and formed in their rear edges (see Fig. 3) with notches g and at their extreme lower ends with rearwardly facing lugs or shoulders g¹. These slides G³ correspond in number to the escapement actuating reeds A² and are arranged below the same with their upper ends in position to control, through trip dogs G⁴, two rows of cam yokes G⁵ the latter being pivoted at their outer ends and disposed horizontally above

80

a pair of rolls G^6 driven constantly by a belt G^7 from the "intermediate" shaft M (see Fig. 1). The inner ends of the yokes G^5 are located directly beneath the respective reeds A^2 , so that when a slide G^3 is raised, the cam yoke associated therewith will be released by the intervening trip dog and its rotary cam allowed to engage the periphery of the underlying roll G^6 . This engagement causes rotation of the cam and the upward rocking of the yoke, which latter is adapted in turn to engage the reed above and lift it to actuate a corresponding escapement.

These power operated devices are essentially the same as those employed in the standard linotype machine, and a more detailed description thereof is therefore unnecessary.

The slides G^3 are raised by means of spring-actuated detents G^8 mounted in the frame G beneath the respective slides, and are returned to their lower position against the action of the detents by a bar J common to all of the slides and arranged in engagement with the lugs g^1 . The bar J is suspended from the frame G near the opposite ends thereof by a pair of links J^1 and is movable longitudinally in opposite directions to lock and release the slides G^3 . A pull spring J^2 , connected to the bar at the extreme right and anchored to a fixed bracket O of the main frame, holds the bar resiliently in its locking position, and a solenoid J^3 (Fig. 2) is employed to swing the bar against the tension of said spring to its releasing position. The solenoid J^3 is supported by a fixed bracket arm J^4 , and its core member is provided with a finger J^5 , which projects forwardly therefrom and engages in a transverse aperture formed in the bar J .

The operation of the vertical slides G^3 is controlled by a series of six horizontal main notched locking bars K and a master or auxiliary notched locking bar L , all of which are slidably mounted in the frame G for a slight longitudinal movement in opposite directions and are arranged in superposed spaced relation with their front or notched edges engaged with the respective notches g of the slides G^3 .

The master bar L (the lowermost one of the series) is shorter than the bars K and is sustained at its opposite ends by pin and slot connections (not shown), which also serve to limit its longitudinal movement. Such movement of the bar L is effected by means of a pair of special slides L^1, L^2 (Fig. 2) located respectively adjacent the opposite ends of the bar and which, in many respects, are similar to the slides G^3 , being formed with corresponding notches l and at their lower ends with lugs l^1 for engagement with the retaining bar J . Unlike the slides G^3 , however, the special slides L^1, L^2 are also formed with beveled cam surface l^2 (Fig. 4) and, moreover, have no connection whatever with the cam yokes G^5 or the associated reeds A^2 . Their only function is to shift the bar L in one direction or the other as they are raised by means of spring-actuated detents, which are similar to but somewhat larger than the detents G^8 of the slides G^3 so as to be capable of overcoming the frictional resistance presented by the bar L .

The main locking bars K are held resiliently toward the right, under the tension of pull springs K^1 , against a vertical stop plate K^2 , which is secured to the right-hand post G^2 and projects into a recess k formed in each of said bars (Fig. 2). The shifting of the bars in the

opposite direction is effected by a series of magnets K^3 , each bar being connected to an individual magnet and operable thereby independently of the other bars. The several magnets (Fig. 2) are mounted upon and conveniently distributed around a supporting bracket K^4 , which is secured to the fixed bracket O and formed with lateral extensions K^5 , the latter being located adjacent the respective magnets and projecting slightly beyond the outer ends thereof. The locking bars K extend through openings in both of said brackets and are operatively connected to the respective magnets by intermediate plate levers K^6 hinged to the extensions K^5 and provided with contact points K^7 aligned with the magnet cores or poles.

The front edges of the bars K are formed with notches k^1 and intervening teeth or locking portion k^2 (see Fig. 2). The arrangement of these notches in the respective bars is such that by shifting the bars singly or in groups a slight distance to the left, they will provide a series of releasing combinations, one for each of the slides G^3 . Since but six locking bars K are employed to make up the releasing combinations for the slides G^3 , the highest possible number of combinations available would not be great enough to provide a separate combination for each of the different characters comprised within the normal matrix font of a linotype machine (usually 90 or more), and for this reason the releasing combinations on the bars K are duplicated for the corresponding characters of the upper and lower cases, the master bar L serving by its adjustment in one direction to lock the group of slides controlling the release of the lower case characters when the upper case is being used, and by its adjustment in the opposite direction to lock the group of slides controlling the release of the upper case characters when the lower case is in use. In this connection, it may be stated for the sake of clearness that the special slides, which control the movements of the master bar, are released by separate combinations produced by shifting different groups of the bars K . The mechanism just described is similar to that disclosed in the pending application to Ackerman, Ser. No. 349,240, to which reference may be had, if desired.

The series of magnets K^3 , as indicated by the diagram of Fig. 12, are energized from a generator Y through separate circuits, established by a corresponding series of vertically movable needles or plungers P , which are arranged to cooperate with the symbols in the tape as the latter is fed horizontally, step by step, beneath them. The needles P constitute part of an electrical distributing mechanism, such as that usually employed in connection with tape-controlled type-casting machines and, as illustrated herein, is arranged conveniently adjacent the keyboard H (see Figs. 1 and 2). The tape T , as commonly produced, contains a continuous line of feed perforations t extending longitudinally thereof and groups or rows of perforated symbols t^1 disposed transversely of the tape. These latter perforations are located on opposite sides of the feed perforations and vary in number from one to six.

The tape T enters the distributor at the right (according to Figs. 5 and 6), where it is guided and sustained between an upper plate P^1 and a block of insulating material P^2 , the latter being fastened down upon a ledge or shelf P^3 formed at the upper end of a stand bracket P^4 , which

rises from one corner of a rectangularly shaped base plate P^5 . The top guide plate P^1 is provided with a row of six perforations p divided into groups of three each, to correspond with 5 the symbols in the tape, and are located directly above a corresponding series of elongated mercury wells p^1 formed in the insulating block P^2 . These walls are tapped to admit leads y^1 , which are passed upwardly through an aperture P^6 10 formed in the ledge P^3 and connected to the respective locking bar magnets K^3 .

The plungers P are carried by upper and lower horizontal flanges P^7 , P^8 , respectively, which project forwardly in horizontal planes above the 15 tape from the upper portion of a vertically reciprocating slide P^9 mounted in the stand bracket P^4 . As best shown in Fig. 4, the plungers P are vertically aligned with the terminal wells p^1 and are provided respectively with stop collars 20 p^2 which bank against the upper face of the lower flange P^8 and above which are arranged light coil springs P^3 adapted to react against the upper flange P^7 when the plungers are pushed upwardly. The flanges P are thus normally suspended 25 at a common level with their lower ends just clearing the top plate P^1 , but are capable of yielding independently against the tension of the springs P^3 by contact with the tape when the slide P^9 is moved downwardly to carry the plungers 30 into the wells p^1 .

The operation of the slide P^9 is effected by a cam P^{10} keyed or otherwise secured to a constantly driven shaft P^{11} , which is journalled in end bearing posts P^{12} , P^{13} , rising from the rear 35 edge of the base plate P^5 at the opposite sides thereof. The cam P^{10} is adapted by its rotation to actuate the slide through the medium of a fore and aft lever P^{14} , the downward movement 40 of the slide taking place against the tension of a compression spring P^{15} seated in the base plate P^5 beneath the slide. The lever P^{14} is pivoted about midway of its length to an arm P^{16} projecting upwardly from the bearing post P^{12} and has its front end loosely engaged in a 45 bearing block of insulation p^4 fitted into the body of the slide P^9 . At its rear end, the lever P^{14} is provided with an anti-friction roller p^5 , which rides over the edge of the cam P^{10} as the latter rotates. The shaft P^{11} (see Fig. 1) receives 50 its motion from a small motor P^{17} through a pair of reducing gears P^{18} journalled on a stub shaft P^{19} projecting laterally from the base plate P^5 directly below the shaft P^{11} .

All of the plungers P are charged simultaneously from the positive main Y^1 (Fig. 12) 55 through the slide P^9 , the latter, as will be observed, being insulated from the base plate and provided at its lower end with a contact face P^{20} , which is adapted, when the slide is moved downwardly, to engage a positive branch terminal P^{21} of the generator Y . At such times, the plungers aligned with the perforation symbols t^1 in the tape are allowed to enter the wells p^1 and close a series of the circuits y leading to the corresponding magnets K^3 and thence through the returns z and negative main Z back to the generator Y .

In order to prevent sparks between the ends 70 of the plungers and the mercury wells, which might result in the destruction of the tape, or the carbonizing of the contact points P^{20} and P^{21} , these circuits are made and broken by means of a commutator Q mounted on the shaft P^{11} and presenting high concentric and low or cut-away portions q^1 , q^2 respectively, which, for

reasons about to appear, bear a definite relation to the cam P^{10} . The commutator Q (see Figs. 4 and 6) is constantly charged from the generator Y through a brush Q^1 fastened to a fixed insulating plate Q^2 and is adapted during each rotation to transmit the charge intermittently to the slide P^9 and the spring plungers P . This is accomplished by means of a second brush Q^3 , which is connected by a lead y^2 to the terminal P^{21} , and arranged adjacent the brush Q^1 directly in line with the low portion q^2 of the commutator.

According to the above arrangement, the brush Q^3 will not be engaged by the high portion q^1 of the commutator until the cam P^{10} , through the pivoted lever P^{14} , has moved the slide P^9 downwardly and engaged the contact points P^{20} , P^{21} ; and the cam P^{10} will maintain the slide in its lowermost position until the low portion q^2 of the commutator is brought opposite the brush Q^3 . The different circuits for energizing the magnets K^3 are in this way made and broken while the contact points P^{20} and P^{21} are engaged and the lower ends of the plungers P are still in the mercury wells p^1 . The commutator Q also serves to make and break the circuit which energizes the solenoid J^3 , and which controls the operation of the bar J for returning the slides G^3 to their normal position after they have been released by the locking bars K , it being noted by further reference to the diagram of Fig. 12 that the lead Y^3 to the solenoid J^3 is also taken from the brush Q^3 .

The mechanism employed for feeding the tape T beneath the plungers P may be of any approved construction so long as its operation is synchronized with that of the reciprocating slide P^9 . This mechanism (as best shown in Figs. 5 and 6) consists of a pair of feed rollers R^1 , R^2 arranged one above the other and between which the tape is passed. The shafts of these rollers are journalled in front and rear bearing arms R^3 , R^4 respectively, formed on a subsidiary bracket R^5 fastened to the stand bracket P^4 . The lower roller R^2 is provided with teeth or 110 pins r adapted to engage the feed perforations t of the tape, and the upper roller R^1 is formed with a corresponding peripheral groove r^1 (Fig. 2) to clear the teeth r . The shaft of the lower roller is rotated by means of a ratchet wheel R^6 115 fastened thereon adjacent the rear bearing R^4 and with which is associated a feed pawl R^7 and a retarding detent R^8 , the former being pivotally connected to a lateral arm P^{22} of the slide P^9 , and the latter similarly connected to a 120 lug R^9 projecting from the bearing arm R^4 . By this arrangement, as the slide P^9 is moved downwardly to carry the plungers P through the perforations t^1 of the tape, the feed pawl rides idly over the teeth of the ratchet wheel R^6 , but 125 on the upward movement of the slide the pawl is adapted, as the plungers leave the tape, to engage and turn the ratchet and through the toothed roller R^2 advance the tape to bring the next row of perforations t^1 beneath the plungers 130 P . Thus, as the slide is reciprocated, the ratchet wheel R^6 is rotated intermittently by the pawl R^7 and the tape is advanced, step by step, past the plungers P .

Since, as previously stated, the matrices released from the magazine A may be assembled at a high or low level in the assembling elevator C by merely adjusting the slide plate C^6 back and forth to carry the short rail section of the auxiliary rail C^2 into and out of action, it 135 140 145 150

is proposed, in carrying out the invention, to effect such adjustment automatically by special symbols produced in the tape T. To end this, there is provided a pair of extra vertical slides 5 S^1, S^2 arranged side by side at the extreme left of the keyboard, in line with the slides G^3 (see Fig. 2). These extra slides, like the slides L^1, L^2 , have no connection with the cam yokes G^5 , but are otherwise similar to the slides G^3 , 10 being formed in their rear edges with corresponding notches s to cooperate with the bars K and at their lower ends with lugs s^1 to cooperate with the retaining bar J. In this connection, it will be understood that the slides 15 S^1, S^2 are also adapted to rise under the influence of spring detents (not shown) as the retaining bar is raised, and that their releasing combinations are produced by shifting selected 20 groups of the locking bars K. The particular bars chosen for the release of the slide S^1 are those designated 0—1—2 in Fig. 4, and for the release of the slide S^2 those designated 0—1—3 in said figure. That is to say, when the three 25 locking bars first mentioned are shifted to the left, the slide S^1 will be released, whereas, when the three bars last mentioned are shifted to the left, the slide S^2 will be released.

The operation of the bars K in releasing the 30 slides S^1 and S^2 will be automatically carried out in precisely the same manner as hereinbefore described, when the corresponding symbols in the tape are brought beneath the spring plungers P. The slides S^1, S^2 , in rising, are adapted by means of suitable switch members 35 S^3, S^4 to close separate circuits w , which pass from a second positive branch terminal S^5 of the generator Y, through a pair of small magnets V^1, V^2 , the latter being mounted in a bracket V^3 secured to the assembling elevator C. These 40 magnets face each other and are spaced apart to admit between their respective poles a common armature V^4 formed at the lower end of the actuating lever C^7 , which, as previously 45 stated, operates the U-shaped plate C^6 . The lever C^7 (best shown in Fig. 3) is pivotally attached between its ends to an upright extension V^5 of the bracket V^3 and is provided with a small friction plate c^4 for restraining it against accidental displacement in its different adjusted 50 positions.

The switch members S^3, S^4 are hingedly mounted near the top of the frame G (see Fig. 3) and have their free ends normally resting upon the upper horizontal edges of the respective slides S^1, S^2 , being insulated from each other, as well as from the slides and frame. Each of the switch members is provided with a contact point s^2 and a binding screw s^3 , to which latter are connected the branch leads w for energizing the respective magnets V^1, V^2 (Figs. 4 and 12). The terminal S^5 is fastened to but insulated from a fixed cross bar of the frame-work and is provided with two contact points s^4, s^5 arranged directly above the points s^2 of the switch members S^3, S^4 . The current from the generator Y is transmitted to the terminal S^5 through a commutator S^6 and a pair of brushes S^7, S^8 , the latter being secured to the insulating plate Q^2 and arranged alongside the brushes Q^1, Q^3 . The commutator S^6 is mounted on the shaft P^{11} , from which it is insulated, and is substantially the same in form as the commutator Q before described. The brush 70 S^7 which, (like the brush Q^1 of the commutator Q), is connected directly to the positive main

Y^1 , is constantly engaged with the high concentric surface of the commutator S^6 , while the brush S^8 is intermittently engaged thereby as the commutator is rotated and, through the primary lead w^1 , charges the branch terminal S^5 . The charging of the terminal S^5 is timed to take place immediately after one of the slides S^1 or S^2 has risen and is discontinued before the bar J returns the slide to its normal position, so that sparks between the contact point s^2 and s^4, s^5 may be avoided.

It will now be seen that when one or the other of the special perforation symbols produced in the tape is brought beneath the plungers P, the corresponding group of locking bars (0—1—2 or 0—1—3) will be shifted to the left and cause the release of the associated slide S^1 or S^2 , as the case may be. If the slide S^1 is the one released, the switch member S^3 will be lifted into contact with the point s^4 of the terminal S^5 and, as the latter is charged, a complete circuit through the rear magnet V^1 will be established. The armature V^4 of the lever C^7 is thus attracted to the pole of said magnet V^1 and the lever is operated to withdraw the short rail section C^3 from its active to its inactive position. As the tape is advanced, matrices subsequently released thereby will then be directed to the lower level in the assembling elevator C until the symbol representing the combination for the slide S^2 is brought beneath the distributing plungers P. At this time, the slide S^2 is released and in rising will lift the switch member S^4 into contact with the point s^5 of the terminal S^5 so as to establish a circuit through the front magnet V^2 . As the magnet is energized, the operation of the lever C^7 will be reversed and the short rail section C^3 moved to its active position. Matrices entering the elevator C will then be assembled at the upper level therein, as previously described.

As a result of the foregoing arrangement, the special symbols for effecting the adjustment of the assembler rail may occur in the tape at any predetermined point desired, either a step in advance of a group of symbols representative of a composed line of matrices and spacers, or be included within a group, so that complete lines of roman or italic characters, or lines containing both kinds of characters, may be automatically assembled. The whole operation is entirely automatic, the matrices not only being released under the control of the perforated tape but their level in the composed line being determined in advance by the tape. In fact, as will be remembered, the same locking bars which govern the release of the matrices are employed for the operation of the short rail section of the assembler. Since no matrices are allowed to remain upon the short rail section when in action, its withdrawal can be effected at any time and even though a single matrix may have previously been assembled at the upper level.

Having thus described our invention, what we claim is, as follows:

1. In a typographical composing mechanism, the combination of a magazine containing a set of two-character matrices, escapements controlling the release of the matrices therefrom, a series of power-operated reeds for actuating the escapements, a corresponding series of slides controlling the operation of said reeds, a series of locking bars cooperating directly with the slides and movable to active or inactive position singly or in groups to establish different combinations in controlling the operation of the

- individual reeds, an assembler wherein the released matrices are composed in line, an auxiliary rail section mounted in the assembler and adjustable to different positions to control the level at which the matrices are composed, electrical means for operating the rail, a perforated tape feed mechanism, means responsive to certain symbols in the tape for operating the locking bars, and means responsive to other symbols 10 in the tape for controlling the operation of the assembler rail section.
2. In a typographical composing mechanism, the combination of a magazine containing a set of two-character matrices, escapements controlling the release of the matrices therefrom, a series of power-operated reeds for actuating the escapements, a corresponding series of slides controlling the operation of said reeds, a series of locking bars cooperating directly with the slides and movable to active or inactive position singly or in groups to establish different combinations in controlling the operation of the individual reeds, an assembler wherein the released matrices are composed in line, an auxiliary rail section mounted in the assembler and adjustable to different positions to control the level at which the matrices are composed, electrical means for operating the rail, a perforated tape feed mechanism, means responsive to certain symbols in the tape for operating the locking bars, and means controlled by the locking bars and responsive to the other symbols in the tape for controlling the operation of the assembler rail section.
3. In a typographical composing machine, the combination of a magazine containing a set of two-character matrices, escapements controlling the release of the matrices therefrom, a series of power-operated reeds for actuating the escapements, a corresponding series of slides controlling the operation of said reeds, a series of locking bars cooperating directly with the slides and movable automatically and movable to active or inactive position singly or in groups to establish different combinations in controlling the operation of the individual reeds, an assembler wherein the released matrices are composed in line, an auxiliary rail section mounted in the assembler and adjustable to different positions to control the level at which the matrices are composed, a pair of magnets for operating the rail section, and switches controlled by separate combinations of said bars for closing a circuit to one or the other of said magnets as required.
4. In a typographical composing machine, the combination of a magazine containing a set of two-character matrices, automatic mechanism for effecting the release of the matrices therefrom, an assembler wherein the matrices may be composed at an upper or lower level to bring one or the other of the matrix characters into casting position, a short auxiliary rail section mounted at the receiving end of the assembler and adjustable into and out of action to control the level at which the matrices are composed, a line resistant finger, a star wheel acting in opposition to the finger and arranged to push the matrices off the short rail section when the latter is in action, the said star wheel being formed with reduced portions adapted when the short rail section is out of action to allow the matrices to be composed at the lower level.
5. In a typographical composing machine, the combination of a magazine containing a set of two-character matrices, automatic mechanism for effecting the release of the matrices therefrom, an assembler wherein the matrices may be composed at an upper or lower level to bring one or the other of the matrix characters into casting position, a short auxiliary rail section mounted at the receiving end of the assembler and adjustable into and out of action to control the level at which the matrices are composed, a line resistant finger, a star wheel acting in opposition to the finger and arranged to push the matrices off the short rail section when the latter is in action, a guard or deflector adjustable into and out of the path of the incoming matrices and adapted in the inactive position of said rail section to guide the matrices to the lower level, and automatic means for adjusting the guard and rail section simultaneously.
6. A combination as specified in claim 6, characterized by the fact that the deflector therein referred to is operatively connected to the short rail section so that as the latter is moved out of action the deflector will be moved into action, and vice versa.
7. In a typographical composing machine, the combination of a magazine containing a set of matrices, escapements controlling the release of the matrices from the magazine, a series of power-operated reeds for actuating the escapements, a corresponding series of slides controlling the operation of said reeds, a series of locking bars cooperating directly with the slides and movable to active or inactive position singly or in groups to establish different combinations in controlling the operation of the individual reeds, a perforated tape feed mechanism, and means responsive to certain symbols in the tape for operating the locking bars.
8. In a typographical composing machine, the combination of a magazine containing matrices, escapements controlling the release of the matrices from the magazine, a series of escapement actuating reeds, power-operated devices for actuating the reeds, a corresponding series of trip dogs for controlling the operation of the reeds, means tending constantly to actuate the trip dogs, a series of locking bars cooperating directly with the trip means and movable to active or inactive position to establish releasing combinations for said dogs, a perforated tape feed mechanism, and means responsive to certain symbols in the tape for operating the locking bars singly or in groups in controlling the release of the individual trip dogs and the consequent operation of the corresponding reeds.
9. In a typographical composing machine, the combination of a magazine containing matrices, escapements controlling the release of the matrices from the magazine, a series of es-

capement actuating reeds, power-operated devices for actuating the reeds, a corresponding series of trip dogs for controlling the operation of the reeds, spring-actuated slides for actuating the trip dogs, a series of locking bars cooperating directly with the spring-actuated slides and movable to active or inactive position for releasing the slides to actuate the trip dogs and for lock-

ing them in their inactive position against the tension of their actuating springs, a perforated tape feed mechanism, and means responsive to certain symbols in the tape for operating the locking bars.

WILLIAM ACKERMAN.
